UNITED STATES PATENT OFFICE.

LEWIS GIBBS, OF CANTON, OHIO.

DESIGN FOR A LAWN-RAKE.

SPECIFICATION forming part of Design No. 25,010, dated December 24, 1895.

Application filed March 25, 1895. Serial No. 543,161. Term of patent 14 years.

To all whom it may concern:

Be it known that I, LEWIS GIBBS, a citizen of the United States, and a resident of Canton, county of Stark, State of Ohio, have invented and produced a new and useful Design 5 for Lawn-Rakes, of which the following is a full, clear, and exact description, reference being had to the accompanying drawings, making part of this specification.

My invention relates to a design for lawn-rakes.

In the accompanying drawing I have illustrated the design in perspective.

My design consists of a longitudinal bar B, 15 composed of parallel upper and lower sides C and D, a curved side E, and an open front side. Projecting apparently through and from the bar are a series of U-shaped teeth curved

transverse the bar and visible between the sides C and D.

20

F denotes a tubular extension connected with the bar, and G denotes a handle extending from said tubular extension.

The leading feature of my design is a head or cross-bar C shape in cross-section with 25 curved and U-shaped teeth.

What I claim is—

The design for lawn rakes as herein shown and described.

In testimony whereof I have hereunto set 30 my hand this 17th day of February, A. D. 1895.

LEWIS GIBBS.

Witnesses:

CHAS. R. MILLER,
W. K. MILLER.
